UNITED STATES PATENT OFFICE

JOHN F. HOFFMAN, OF OMAHA, NEBRASKA, ASSIGNOR TO BAKER ICE MACHINE CO. INC.,
OF OMAHA, NEBRASKA, A CORPORATION OF NEBRASKA

REFRIGERATING APPARATUS

Application filed August 1, 1927. Serial No. 209,690.

My invention relates to refrigerating apparatus and more particularly to apparatus of that character wherein a low boiling point liquid, such as anhydrous ammonia, is compressed and circulated through condensing and cooling coils to effect temperature equalization by expansion and evaporation of the refrigerating agent in the cooling coils, the principal object of the present invention being to control supply of the refrigerating agent to the cooling coil by differential in temperature at the ends of the coil and in pressure in the supply and return lines.

It is also an object of the invention to effect the differential temperature and pressure control with a single stage expansion of the refrigerating medium in the supply line.

In accomplishing these and other objects of the invention I have provided improved details of structure, the preferred forms of which are illustrated in the accompanying drawings, wherein:

Fig. 1 is a diagram of a refrigerating system embodying my improvements, some of the parts being in section and magnified for better illustration.

Fig. 2 is an enlarged, central, vertical section of the valves constituting the unified control of supply of the refrigerating agent.

Referring more in detail to the drawings:

1 designates a compressor operable by an electric motor 2; 3 a condenser connected with the compressor through a line 4; 5 a receiver at the outlet end of the condenser; 6 a line leading from the receiver through controlling mechanism to a cooling coil 7 and including a sediment trap 8; 9 a return line from the cooling coil to the compressor; 10, 11 high and low pressure gauges connected with the supply and return lines through the branches 12 and 13; and 14 a charging line, all in accordance with common practice, the present invention relating to improved means and apparatus for automatically controlling and regulating supply from the condenser to the coil.

The system may be controlled manually or automatically but I prefer to employ automatic control through a thermostat 15 located within the compartment served by the

coil 7 and operable on a switch 16 in the circuit 17 serving the motor, so that when temperature of the compartment rises to a predetermined degree, the motor is automatically started to operate the compressor, and when the temperature falls to the proper degree the motor is cut off to stop the compressor.

The unified control for the supply of refrigerating agent to the coil includes a valve 18 indicated generally 18, and comprising a valve housing body 19 and cap 20 connected by the flange bolts 21.

The body 19 has a channel 22 receiving the threaded end 23 of the line 6 and opening 25 freely into a chamber 24 in the top of the body.

Extending into the chamber 24 and terminating in a ground surface flush with the top of the body is a boss 25. Leading 70 through the boss is a channel 26 of the same capacity as the channel 22, having a port 27 in the top of the boss constituting the top of the boss a valve seat.

Threaded into the outlet end of the channel 26 is a connecting line 28 constituting a continuation of the supply line 6.

The cap 20 encloses a vertical chamber 29 having an enlarged lower portion forming a shoulder 30 and containing a spring seat 31 80 which rests on a diaphragm 32 separating the chamber 24 in the body 19 from the chamber 27 in the cap 20, the periphery of the diaphragm being located between the body and cap flanges and held in place by the flange 85 bolts 21.

The spring seat 31 receives the lower end of an expansion spring 33 which yieldingly urges the diaphragm to contact with the top of the boss 25 to close the outlet port and interrupt flow through the supply line.

The spring at its upper end bears against a guide plate 34 engageable by a set screw 35 threaded through the upper end of the cap and held in adjusted position by a lock nut 36.

Opening from the chamber 29 is a channel 37 receiving the threaded end 38 of a line 39 which communicates with the return line 9 and is provided with a manual valve 40.

With this arrangement the valve 18 is nor- 100

mally closed under tension of the spring 33 but will open under pressure of liquid in the supply line when the pressure of the liquid is sufficient to overcome combined tension of the 5 spring and pressure in the return line, it being apparent that freedom of flow through the valve may be regulated by adjustment of tension of the spring 33.

The continuation 28 of the supply line is 10 provided with a pressure indicator 41.

Interposed in the continuing line 28 between the indicator 41 and the coil is a temperature controlled valve indicated generally by the housing 42 and comprising a body 15 member 43 and its cap 44. Formed in the body member is a chamber 45 closed by a plug 46 and into which the continuing line delivers through its threaded terminal 47.

Leading from the chamber 45 is a duct 48 20 which opens to a chamber 49 formed partly within the body 43 and partly within a cap 50 suspended from the body 43 by a bolt 51. The chamber 49 communicates through a throat 52 with a chamber 53 in the body 43, 25 the upper part of the chamber being preferably enlarged at 54 to provide a substantial area of contact of refrigerating agent with a diaphragm 55 interposed between the body 43 and cap 44 and held in place by the bolts 30 56 which attach the cap 44 to the body 43.

A duct 57 leads from the chamber 53 to supply refrigerating agent from the chamber to the coil 7, the end of the coil being threaded into the outlet end of the duct.

35 Extending through the throat 52 into the chamber 53 is a tube 58 having a head 59 clamped against the top of the chamber 49 by a collar 60 threaded into the upper portion of the chamber above the outlet of the duct 48.

40 Supported on the bottom of the cap 50 about a boss 61 is an expansion spring 62 carrying a seating plate 63 which supports a valve ball 64 within the collar 60, and urges the ball to contact with the open lower end of 45 the tube 58, thereby constituting the end of the tube a valve seat.

Supported on the ball 64 and extending through the bore of the tube 58 is a squared pin 65.

50 Slidable on the upper end of the tube 58 is a sleeve 66 having a rounded head 67 engaging the diaphragm 55 at its upper face and contacted by the squared pin 65 on its under face. The sleeve 66 is provided with 55 port openings 68 and the tube 58 with openings 69 through which fluid may pass from the tube to chamber 53 when the valve 64 is open, as will presently be described.

The cap contains a chamber 70 enlarged at 60 its lower end to provide the shoulder 71. Slidable in the enlarged portion of chamber 70 for vertical movement limited by the shoulder 71 is a cup 72, seating an expansion spring 73 engaging at its upper end a thrust plate 74 adjustable by set screw 75 which

extends through the top of the cap and held in adjusted position by a lock nut 76. The spring 73 tends to expand the diaphragm 55 downwardly to push the pin 65 against the valve ball 64 to open the valve and provide 70 flow through chamber 53 to the coil.

Opening through the cap 44 from the chamber 70 is a port 77 through which the chamber communicates with a channel 78 into which is threaded the end of a line 79 leading to and communicating with an annular chamber 80 within a housing 81 on the line 9 adjacent the outlet end of the coil 7.

The port 77 also provides communication between the chamber 70 and the channel 82 80 into which is threaded the nipple 83 of a valve housing 84 containing a valve not shown but indicated by the hand wheel 85. The housing 84 is connected with the filter chamber 45 of the valve 42 whereby the refrigerating liquid admitted to the filter chamber through the continuing line 28 may be by-passed around the valve to the chamber 70 and through the line 79 into the chamber 80 to supply the chamber 80 with a quantity 85 of such liquid and constitute such supply a thermostatic agent. 86 designates a temperature indicator on the line 79.

Assuming the parts to be constructed and assembled as described, the system may be 90 operated as follows:

Air is first drawn from the system by operating the compressor with the charging line 14 closed, and the valves 40 and 84 open until 100 vacuum is indicated on the gauges 10—11, 41 and 86. The valves 40 and 84 are then closed and the system charged through the line 14 in accordance with common practice.

At this point a pressure of, for example, 110 pounds will be indicated at 10, 50 pounds 105 at 11, 50 pounds at 41, and a vacuum indicated at 86 because of the closure of the valve 84 after the air removal and prior to charging of the system with the refrigerating agent.

110 The compressor is then put in operation and under automatic control responsive to temperature in the compartment served by the system, the refrigerating liquid being forced through the condenser and receiver 115 into the pressure regulated valve 18 of the unified control. When this flow takes place pressure in the supply line is raised to, for example, 185 pounds, as indicated on gauge 10, and pressure in the return line is lowered; 120 consequently refrigerating liquid entering the valve 18 expands the diaphragm 32 against the reduced pressure on the low pressure side, and the liquid flows beneath the diaphragm and out through the channel 26 into the connecting line 28 and to the filter chamber in the valve housing 40, without reduction in the valve 18, the gauge 41 showing the same pressure as the gauge 10 at the compressor side of the valve.

The valve 84 is then opened to permit liquid to by-pass into the upper valved chamber 70 and through the line 79 to the chamber 80 in the housing 81 about the return line, 5 until the gauge 86 shows a pressure of about 25 pounds less than that in the supply line. The valve 84 is then closed to trap the charge of liquid and retain it as a thermostatic medium for the purposes presently described. 10 Such pressure of the liquid in the upper valve chamber 70 is sufficient to overcome the spring 62 and lower the ball 64 from its seat, opening a passage from the lower valve chamber 49 through the tube 58 into the valved chamber 53 to permit flow of the refrigerating liquid through the valve into the coil 7 and back through the return line to the compressor.

Gaseous component of the liquid trapped 20 in the line 79 and housing 81 is subject to temperature in the return line from the coil which originally is sufficient to expand the contents of the housing and line and exert a pressure on the diaphragm 55 sufficient to 25 maintain the valve open and permit flow of refrigerant to the coil. As flow continues through the coil there is a temperature exchange tending to cool the compartment served by the coil, but as the temperature in 30 the compartment is lowered, the temperature of the refrigerating agent is also lowered until eventually such decrease in temperature reacts on contents of the housing 81 and such contents are contracted, relieving the valve 64 35 and permitting the valve to close. Supply of refrigerant to the coil is then cut off at the unified control and temperature of the compartment being at a sufficiently low degree, the motor is shut off through the thermostat 40 15. When the compressor is stopped, pressure accumulating in the return line is transmitted to the diaphragm in the valve 18 to close the valve so that the supply line is closed at valve 18 as well as at valve 42. The system then remains idle until temperature in 45 the compartment served by the coil rises to a degree requiring further refrigerant. As temperature in the compartment rises, temperature of contents of the coil also rises, expanding contents of the housing 81 and opening the temperature controlled valve 42 in the supply line, but more firmly closing the pressure controlled valve 18 in said line.

When temperature in the compartment has 55 risen sufficiently to operate the thermostat, the compressor is started in operation, building up pressure in the supply line and exhausting content of the return line until pressure in the return line has reached a degree at 60 which the valve 18 is opened under pressure in the supply line. Refrigerant then flows through the open valves and coil, back through the return line until the compartment has been brought back to the proper temperature and the valves operated as before.

It is apparent, therefore, that with the apparatus described, I provide a double control of the refrigerant supply with but a single reduction of pressure, as flow through the valve 18 is free when the valve is open.

It is further apparent that the valve 18 is quick opening or closing under pressure control and that when the diaphragm seats there is complete closure of the flow without tendency to leakage because of imperfect co-operation of valve parts.

With such an arrangement a large volume of cooling medium may be employed with a comparatively small apparatus capable of close regulation.

What I claim and desire to secure by Letters Patent is:

1. Refrigerating apparatus, including a compressor, a cooling coil, supply and return lines connecting the compressor with the coil, and synchronizing means including separate valves in the supply line, respectively responsive to temperature and pressure in the return line controlling flow through the supply line.

2. Refrigerating apparatus, including a compressor, a cooling coil, supply and return lines connecting the compressor with the coil, independent free flow and reduction valves interposed in the supply line, one responsive to differential pressures in the supply and return lines, and the other responsive to variable temperatures in the return line.

3. Refrigerating apparatus, including a compressor, a cooling coil, supply and return lines connecting the compressor with the coil, independent free flow and reduction valves interposed in the supply line, one responsive to differential pressures in the supply and return lines, and the other responsive to variable temperatures in the return line, and a pressure gauge on the supply line between said valves.

4. Refrigerating apparatus including a compressor, a cooling coil, a valve housing having separate chambers, one communicating with the return line, the other having a valve seat and communicating with the compressor and coil at opposite sides of said seat, a diaphragm separating said chambers and cooperative with said seat to close the line of communication from the compressor to the coil, and a spring yieldingly urging the diaphragm to said seat, the diaphragm being responsive to change in pressure in the chamber communicating with the return line to open and close the valve.

In testimony whereof I affix my signature.

JOHN F. HOFFMAN.
